C. F. P. Schaefer
C. F. Hensel *H. W. Hensel*

Des. 1827

H. W. Kensis, of Philadelphia, Penn.
Letters Patent No 1827-Dated Oct. 6th 1863.

Antedated July 7, 1863.

Design for Blind Binding.

~~~~~

The schedule referred to in these Letters Patent and making part of the same.

~~~~~

To all whom it may concern:

Be it known that I, H. W. Kensis of the City and County of Philadelphia, State of Pennsylvania, have invented or produced a new and original design for Blind Binding; and I do hereby declare the accompanying drawing, with the following explanation of the same, to form a full, clear and exact description of the said design.

The drawing represents sufficient of a strip of blind binding to illustrate my design.

In the centre of the figure constituting the design, are two roses A and B. From a cluster of leaves C, above the roses A, projects a forked stem bearing on one branch a full rose D, and on the other branch a bud E.

From a cluster of leaves C', below the rose B, project two stems each bearing on its end a partly opened bud E.'

Irrespective of the material and colors used in the production of the design, and irrespective of the

edging shown, & claim the ornamental figures and forms represented in and by the accompanying drawing; the whole forming an ornamental design for a blind binding.

On testimony whereof I have signed my name to this specification, in the presence of two subscribing witnesses:

Witnesses:

Charles E. Foster, }
C. Hunsberger. }

H. W. Hensel.
